FREE RUNNING SPINNING RING

Gompei Kuwada, Maetani-Mura,
Kawabe-Gun, JapanApplication October 22, 1934, Serial No. 749,426
In Japan August 18, 1934

5 Claims. (Cl. 118—59.5)

My invention relates to an improvement on spinning ring and its holder. In the drawing Fig. I is a vertical cross section of the ring placed in its holder. Fig. II is part plan and part horizontal section of the same; in which 1 is the ring, 3 is the ring holder, 7 is a groove in the holder with an oiled wick placed therein, 8 is an open ring of metal wire, 9 is a groove on the interior of the holder, 10 is a groove on the exterior of the ring and 11 is the opening between the ends of the ring 8.

The feature of my invention consists in leaving the ring free to rotate within its holder but preventing the ring from being lifted by yarn tension, the object being to ease off the effect on travellers caused by uneven tension stresses of yarn being spun.

As shown by the drawing, the ring has a groove 10 on its exterior and the holder a corresponding groove 9 on its interior. In the latter groove there is placed a ring 8 of metal wire open in one part, as at 11 and the ring 1 snapped in is thereby held from being lifted but remains free to rotate within the holder 3.

25 In the groove 7 there is provided an oil wick which is in contact lightly with the bottom face of the ring, which acts as a brake on the ring in case the ring is caused to rotate too freely.

Having thus described my invention what I

30 claim is:

1. A device of the class described, comprising a ring holder, a spinning ring rotatably mounted in said holder, said ring and said holder having cooperating grooves in opposed faces, and an open-ended metallic ring positioned in the space defined by said grooves and preventing the spinning ring from being lifted out of the holder.

2. A device of the class described, comprising a ring holder, a spinning ring rotatably mounted in said holder, said ring and holder having cooperating grooves in opposed faces, and an open-ended metallic spring ring carried by the spinning ring and positioned in the groove formed therein, said spring ring extending beneath the

upper edge defining the groove in the ring holder and thereby preventing the spinning ring from being lifted out of the holder.

3. A device of the class described, comprising a ring holder internally shouldered at its upper end to provide horizontal and vertical faces, a spinning ring seated on said horizontal face and having a vertical face opposite the vertical face of the holder, said vertical faces having grooves therein opposite one another, and an open-ended 10 metallic spring ring positioned in the space defined by said grooves, said spring ring preventing the spinning ring from being lifted out of the holder.

4. A device of the class described, comprising a 15 ring holder internally shouldered at its upper end to provide horizontal and vertical faces, a spinning ring seated on said horizontal face and having a vertical face opposite the vertical face of the holder, said vertical faces having grooves 20 therein opposite one another, an open-ended metallic spring ring positioned in the space defined by said grooves, said spring ring preventing the spinning ring from being lifted out of the holder, the horizontal face of said holder on which 25 the spinning ring seats being grooved, and an oil wick positioned in and substantially filling said groove.

5. A device of the class described, comprising a ring holder internally shouldered at its upper 30 end to provide horizontal and vertical faces, a spinning ring seated on said horizontal face and having a vertical face opposite the vertical face of the holder, said vertical faces having grooves 35 therein opposite one another, and an open-ended metallic spring ring carried by the spinning ring and positioned in the groove formed in its vertical face, the upper edge defining the groove in the vertical face of the ring holder vertically overlying the spring ring, whereby said spring ring 40 prevents the spinning ring from being lifted out of the holder.

GOMPEI KUWADA.
